UNITED STATES PATENT OFFICE.

SEAMAN A. WILLIAMSON, OF POINT RICHMOND, CALIFORNIA.

AEROPLANE.

1,407,505.

Specification of Letters Patent. Patented Feb. 21, 1922.

Application filed February 12, 1921. Serial No. 444,408.

To all whom it may concern:

Be it known that I, SEAMAN A. WILLIAMSON, a citizen of the United States, residing at Point Richmond, in the county of Contra Costa and State of California, have invented new and useful Improvements in Aeroplanes, of which the following is a specification.

This invention relates to aeroplanes and similar aerial vessels and has primarily for its object to devise an efficient means whereby the ascent, or the too rapid descent of the vessel is controlled according to the adjustment of the regulating means provided therefor.

Another object of this invention is to provide means disposed adjacent the center of gravity for balancing the aeroplane, which means is adapted to be used for ascending and likewise descending, and which precludes possibility of the usual dipping when passing through varying atmospheric zones, and also in no way interfering with the operation of the aeroplane or retarding its movement.

A further object of this invention is to provide an improved mechanism positioned in close proximity to the body of the aeroplane, which is manually controlled by the operator and easily adjusted to various positions.

A still further object of this invention is to provide a support for the stabilizing means for the aeroplane which can be readily applied thereto without materially altering the construction of the same.

Other objects and advantages of the invention will be apparent during the course of the following description:

In the accompanying drawings forming a part of this specification, and in which like numerals are employed to designate like parts throughout the same,

Figure 1 is a view of the machine in side elevation,

Figure 2 is a top plan view of the same,

Figure 3 is a central vertical transverse section of the means for controlling the vertical propeller,

Figure 4 is a central vertical longitudinal section of the same, and

Figure 5 is a horizontal sectional view taken on the line 5-5 of Figure 3.

In the accompanying drawings wherein for the purpose of illustration is shown a preferred embodiment of my invention, the

numeral 6 designates the body of the aeroplane which is provided with upper and lower sustaining planes 7 and 8, the upper plane being slotted as shown at 8'. 60

In the body of the aeroplane there is mounted the usual motor 9 which controls the propeller shaft 10 carrying the usual propeller 11 disposed at the front end of the body 6. This construction is of the conventional type and forms no part of my invention. 65

The numeral 12 designates a pair of supporting guides detachably fastened at their free extremities to the body of the aeroplane 6. 70

Disposed between and connecting the guides is a cross piece 13 provided with a centrally located upper bearing 14. As shown to advantage in Figure 3, the cross piece is likewise provided with apertured extremities 14' adapted to encircle the guides 12. 75

Suitably mounted within the body 6 is a base support 15 provided with vertical standards 15' adjusted to receive therein a shaft 16. The numeral 17 designates a frame as a whole, which includes a yoke member 18 and an upper portion 19 formed integral with the cross piece 13. Formed in the lower extremity of the yoke member 18 is a gear segment 20 adapted to mesh with a worm 21 provided on a control shaft 22 journaled in extensions 23 formed integral with the base support 15. The numeral 23' designates a control column and 23" indicates a universal coupling adapted to actuate the shaft 22 upon movement of the control column 23". 90

This construction is set forth in Figures 95 3 and 4, while in dotted line position in Figure 1 there is shown the means for controlling the action of the worm on the gear segment.

From this construction it will be apparent that movement of the worm will cause the frame to assume various angular positions. 100

Formed integral with the upper portion of the yoke 18 is a lower bearing 24, which 105 together with the upper bearing 14 encircle a normally vertical propeller shaft 25, which has on its lower extremity a beveled gear 26 and likewise carries on its upper extremity an auxiliary or horizontally disposed propeller 27 adapted to rotate on a vertical axis and designed for use in ascend- 110

ing or descending, which use will be hereinafter more fully described.

In order that the weight of the propeller shaft may be supported on the bearing 24, 5 I have provided a collar 28 which rests on the bearing and rotates with the shaft. The collar 28 is provided with a flat face 29, whereby the rotating action of the shaft may be gradually checked when a pivoted 10 arm 30 is swung from its normal vertical position to its retarding position, as shown in dotted lines in Figure 3, and in detail in Figure 5.

It will thus be evident that means are 15 provided for checking the rotation of the vertical propeller shaft and thus overcoming the air resistance offered by the horizontal or auxiliary propeller when its purpose has been accomplished.

20 Meshing with the gear wheel 26 is a master gear 31, which in turn has meshing therewith for the purpose of driving the same, a second bevel gear 32 mounted on a sectional engine shaft 33 which has associated therewith a friction clutch 34 of the conventional type. For the purpose of supporting the engine shaft and its associated clutch, a standard 34' has been provided which is integrally formed with the base 30 member 15.

It will thus be evident that means are provided for throwing the vertical propeller shaft out or for driving the same when so desired, according to the manipulation of 35 a lever, (not shown) under control of the operator.

When the clutch is thrown in, not only can this propeller shaft be maintained in its normal vertical position, but it can also 40 be moved fore and aft by the actuating of the control column 22 which has its worm meshing with the segment 20, which action will cause the auxiliary propeller to assume different angular positions.

45 Thus when the operator of the aeroplane desires either to assist in the ascent or to check the descent of the aeroplane, he can readily have the stabilizing means assume either of the dotted line positions shown to 50 advantage in Figure 1.

In operation therefore, assuming that the operator wishes to employ the auxiliary propeller to assist in the ascent, the driving propeller is started, then the clutch is 55 thrown in and through the action of the bevel gear 32 on the master gear 31, the auxiliary propeller is rotated. When this action occurs, the operator by a manipulation of the control column causes the worm

21 to mesh with the segment 20 and impart 60 a rocking movement to the frame 17, and thus the vertical propeller shaft assumes a fore position.

When the desired altitude has been reached the clutch is thrown out and the 65 propeller shaft is returned to its normal vertical position and the auxiliary propeller gradually checked from rotation through the interrupted contact of the flat face of the collar 28 on the pivoted arm 30.

70 On the other hand, when a landing is to be made, the same operation as above described for causing the auxiliary propeller to operate, is repeated, but only with a reverse movement of the control wheel. The 75 auxiliary propeller will then assume an aft position and the speed of the aeroplane can to a great degree be checked so that a landing can be made on a comparatively small area.

80 It is to be understood that the form of my invention, herein shown and described, is to be taken as a preferred example of the same, and that various changes in the shape, size and arrangement of parts may be resorted to without departing from the spirit of the invention, or the scope of the subjoined claims.

85 Having thus described my invention, I claim:—

1. In an aeroplane, a body portion, a pair of sustaining planes mounted thereon, one of said planes being slotted, a main driving propeller, an auxiliary propeller, a sectional engine shaft for driving said main propeller 95 and said auxiliary propeller, a clutch mounted on said sectional shaft for alternately throwing said auxiliary propeller into and out of engagement with said engine shaft, a frame positioned within the 100 body portion of said aeroplane for supporting said auxiliary propeller, and means under the control of an occupant for rocking said frame to cause said auxiliary propeller to assume different angular positions.

105 2. In an aeroplane, the combination with a body portion, of sustaining planes mounted on said body, a driving propeller, an auxiliary propeller, a frame positioned in the body of said aeroplane and adapted to hold said auxiliary propeller, mechanism for rocking said frame, and a universal coupling connected to said mechanism and adapted to control the different angular positions of said auxiliary propeller.

110 115 In testimony whereof I affix my signature.

SEAMAN A. WILLIAMSON.
